Patented June 14, 1921.

FIG. 1.

FIG. 2.

34 30 13 32
FIG. 4. 26 FIG. 5

FIG. 6.

INVENTOR:

William H. Burns
BY HIS ATTORNEY:
A. M. Carlsen.

UNITED STATES PATENT OFFICE.

WILLIAM H. BURNS, OF ST. PAUL, MINNESOTA.

SLIDING-DOOR FASTENER.

1,381,891.

Specification of Letters Patent. Patented June 14, 1921.

Application filed November 30, 1920. Serial No. 427,420.

To all whom it may concern:

Be it known that I, WILLIAM H. BURNS, a citizen of the United States, residing at St. Paul, in the county of Ramsey and State 5 of Minnesota, have invented a new and useful Sliding-Door Fastener, of which the following is a specification.

My invention relates to car-door locks, particularly adaptable for use on railway 10 box cars, and the object of the invention is to provide a semi-automatic device of simple construction and positive action when closing the door of a car or other structure having a sliding door.

15 This object I attain by the mechanism illustrated in the accompanying drawing, in which,—

Figure 1 is a side elevation of a box car with my device applied to it in operative 20 position near its door.

Fig. 2 is an enlarged horizontal sectional view on line 2—2 of Fig. 1.

Fig. 3 is a side elevation of the device as attached to the door frame of a car.

25 Fig. 4 is a partly sectional side elevation showing a modified construction of the device on a reduced scale.

Fig. 5 is a sectional elevation on line 5—5 in Fig. 4.

30 Fig. 6 is a section on line 6—6 in Fig. 1 showing a certain detail.

Referring to the drawing by reference numerals, 6 designates a railway box car, with sliding side door 7, the upper part of which, 35 has rollers 8 rolling on a rail 9, and the lower part of the door is suspended between the car body and a guide rail 10.

My device has its working parts mounted in a cast frame or bracket 11 which has a 40 vertical plate 12 bolted as at 13 to the vertical side member 14 of the door frame, that is near the rear edge of the door when closed. 15 is the door opening. Said frame 11 has an upper horizontal arm 16 and a lower one 45 17 parallel thereto. A vertical and rotatable headed pin 18 is passed through said arms and may have a cotter pin 19 near its lower end to hold it in place. On said pin, between the arms 16 and 17 I place a locking arm 20 and a toothed sector 21 on top of it, both held in right relative position and to the pin 18 by a key 22 for a purpose to be described. Or I may cast or secure the arm 50 and the toothed sector together and place them loosely on the pin 18.

The arm 20 has a finger 23, which, when

the door is shut, assumes the position shown in Fig. 2, holding the door 7 closed, the arm being locked by a vertically slidable key 24, which when down takes against the elbow 60 25 of the arm 20. Said key 24 is a plate having a downwardly extending tongue 26 65 slidable through a corresponding hole 27 in arm 17, the upper or plate portion sliding through slot 28 in arm 16; the shoulder 29 of the key therefore rests on arm 17 when in locking position back of the elbow 25. The arm 17 of the bracket 11 has a downwardly 70 projecting lug 30 cast integral with it, said lug corresponding in size and being parallel to arm or tongue 26 of the key. A hole 31 in tongue 26 and hole 32 in lug 30 are exactly opposite when key is in locked position, thus permitting a wire 50 (Fig. 1) or other seal strap to be passed through them and 75 sealed, thus conforming with the law requiring box cars to be sealed after being loaded.

When the car door is to be opened the seal is broken and removed, then tongue 26 of key 24 is pushed upward approximately to 80 the dotted position 24, so that its edge 29 clears the arm 20, the door is pushed to the right and a rack 33 secured on the inner side of the door engages the teeth of segment 21, turns the arm 20 to the dotted position 85 20—23 in Fig. 2. The backward swing of the arm, as soon as the last tooth of the rack 33 passes out of engagement with the sector 21, leaves the door free to be pushed fully open. The cam or arm 20 is held in un- 90 locked (dotted) position by the locking key plate dropping into a shallow groove 34 provided in the top of the cam. In said position of the cam its finger 23 takes the position 23^a, which is out of the way of the moving door (see Fig. 2). A pin 35 on the key 24 limits the upward movement of the key and may also serve as a catch to lift the key. 95

In the modification Figs. 4 and 5, the arm 16 of bracket 11 has a vertical arm 36. The locking key is changed above the arm 16 only in that it is extended to the same height as the arm 36, has a vertical slot 37 and at its upper end is bent out to form a finger hold 38. A shoulder-bolt or cap screw, 39, inserted in the slot and screwed into arm 36 guides the key plate vertically and a flange 40 on lower part of arm 36 also prevents the key plate from slipping edgewise. 100 105

Near the lower right hand corner of door 110 opening I provide a guide bracket 41 secured in any suitable manner to the car body

and having an upwardly extending arm 41^x spaced such a distance from the car that when the door is moved to the left to be closed, a wedge shaped piece 42 secured on the door and having a straight edge 43 engages the bracket 41, thereby positively bringing ratchet 33 in mesh with gear sector 21, which by turning lifts key 24 out of the shallow groove 34 of the cam and swings 10 the arm 20 into position shown in full lines in Fig. 2, and then key 24 drops down back of the arm 20 and the door is securely held shut.

The operation of my device being quite 15 fully described in the above description, it needs only be further mentioned that the design of the gear and rack mechanism must be such that when the door and its rack are moved to the right, the last tooth 21^x on 20 the sector turns to position 21^{xx}, at which time the groove 34 of arm 20 is engaged by the locking key 24 and the point 44 of the cam simultaneously meets the surface of the bracket as at 45 (Fig. 2). When tooth 21^x 25 reaches said position 21^{xx}, the last tooth of the rack is in position 33^{xx} and the door can then be pushed further open with the gear sector and rack out of mesh. On closing the door by pushing it to the left the tooth 33^{xx} 30 first engages tooth 21^x and the rest mesh in rotation, affecting the arm 20 as above described.

When the car side is of the kind composed of an inner and an outer member spaced by 35 interposed posts I cut an opening 51 in the outer member for the insertion of the device, as shown in Fig. 1.

What I claim is:

1. The combination with a car and the 40 sliding door of same, of a metal frame secured on the side of the car near the door opening, an arm pivoted in the frame and arranged to engage the rear edge of the door to resist opening of it, means on the 45 door for automatically bringing the arm to the resisting position during the closing of the door, and an automatically moving lock-

ing member engaging the arm to hold it firmly in the resisting relation to the door.

2. The structure specified in claim 1, said 50 arm having a finger or portion projecting upon the outer side of the door.

3. The structure specified in claim 1, said 55 arm arranged to swing in horizontal plane and having in its upper side a shallow groove, and the locking member being guided to slide vertically in the frame and having a portion arranged to engage in the shallow groove when the member is raised, whereby both the arm and its locking member are held against accidental movement 60 when in unlocked position.

4. The structure specified in claim 1, said 65 engaging means between the door and the arm consisting of a toothed sector fixed on the arm and a short rack fixed on the door near the rear edge of it.

5. The structure specified in claim 4, and 70 means on the car and on the door for so guiding the door that the rack will engage the toothed sector.

6. The structure specified in claim 1, said 75 frame and locking member having each a portion with a hole through it for the strap of a car seal.

7. The structure specified in claim 3, and 80 means for positively stopping the opening movement of the arm when its groove is directly below the portion of the locking slide designed to engage therein.

8. The combination with a structure having 85 a door opening and a sliding door arranged to close the opening, of an arm pivotally mounted on the structure and having a toothed sector, a rack fixed on the door and arranged to engage the sector while the door is being closed and thus bring the arm across the rear edge of the door when the latter is shut, an automatically operated locking member arranged to engage and hold the arm in locking position, and means 90 for sealing the locking member.

In testimony whereof I affix my signature.

WILLIAM H. BURNS.
